UNITED STATES PATENT OFFICE

CHARLES F. HUMPHREYS, OF LANCASTER, PENNSYLVANIA, ASSIGNOR TO ARMSTRONG CORK COMPANY, OF LANCASTER, PENNSYLVANIA, A CORPORATION OF PENNSYLVANIA

SURFACE COVERING SUCH AS LINOLEUM

Application filed May 7, 1929. Serial No. 361,095.

This invention relates to surface covering such as linoleum and provides a surface covering which in itself may possess highly desirable ornamental effects or which may 5 form an intermediate product in the production of linoleums or the like of improved appearance.

A large amount of linoleum is made on rotary machines. These machines while 10 capable of very rapid production are relatively limited in the number of colors which may be employed and in the character of the patterns made. For this reason a large 15 number of linoleum patterns are not applicable to manufacture by the rotary machine despite the advantage of low cost which it offers. The rotary machine comprises essentially a drum having die rolls arranged around its periphery which die rolls are effective for cutting out pattern elements and 20 applying the same to a backing as it moves with the drum. A separate die roll is required for each color used in the pattern. Prior to my invention the die rolls have always 25 been used to entirely cover the backing. I provide for covering a portion only of the backing so that it is exposed between pattern elements. Desirable effects may thus be secured. In certain cases some or all of 30 the exposed portions of the backing may be filled in by other pattern elements. For instance, brightly colored pattern elements may be filled in by hand and calendered to the backing.

My improved process and the machine for carrying the same into effect are more fully described and claimed in my co-pending application Serial No. 363,581 filed May 16, 1929. The present application is directed 40 to the material itself.

In the accompanying drawing illustrating different forms which my invention may take,

Figure 1 is a top plan view of a piece 45 of my improved linoleum,

Figure 2 is a top plan view of another form thereof, and

Figure 3 is a view of a piece of the linoleum of Fig. 2 after it has had additional 50 pattern elements applied thereto.

Referring first to Figure 1, there is shown a linoleum comprising a backing 2 having pattern elements 3 applied thereto. The backing consists of a burlap web 4 having an overlying coating 5 of linoleum mix. The pattern elements 3 are applied to this coating 5 and are firmly secured thereto as by calendering or cementing. As shown in Fig. 1, the pattern elements are of different colors so as to form any desired design.

In Fig. 2, I have shown another type of linoleum wherein the pattern elements, instead of being spaced each from its adjacent element, are contiguous. However, certain portions of the web are left exposed as indicated at 11. The pattern elements are indicated at 12 and as shown they are of different colors so as to give the desired effects.

The linoleum pattern elements, of course, have a certain thickness, and hence the base lies at a lower level than the top of the pattern elements.

Fig. 3 shows a piece of linoleum of the type of Fig. 2, wherein some or all of the exposed portions 11 of the web have been filled in by brightly colored pattern elements 21 which provide haphazard spots of color in the pattern. Such spots are desirable in that they break the monotony of a regular pattern and thereby improve the appearance. I have shown at 3a in Fig. 1 brightly colored pattern elements which contrast with the main body of the material.

In the linoleums of Fig. 1 and Fig. 2, the applied pattern elements stand at a higher level than the base material.

I have illustrated and described by way of example only two types of linoleum made according to my invention. It will be understood that the invention is not limited to such forms but may be otherwise embodied within the scope of the following claims.

I claim:

1. As a new article of manufacture, a surface covering comprising a base made up of a fabric web and a substantially continuously extending layer of linoleum mix thereover and pattern elements of linoleum mix

overlying and secured to the base, the base being exposed between at least some of the pattern elements.

2. As a new article of manufacture, a surface covering comprising a base having a fabric web and whose upper face presents a substantially continuously extending layer of linoleum mix and pattern elements of linoleum mix overlying a portion only of the base, and secured thereto.

3. As a new article of manufacture, a surface covering comprising a base having overlying pattern elements of linoleum mix secured to the base, the base being exposed between pattern elements and lying at a lower level than the top surface of said pattern elements.

4. As a new article of manufacture, a surface covering comprising a base made up of a fabric web and having a substantially continuously extending layer of linoleum mix thereover, and pattern elements of linoleum mix overlying the base and secured thereto, the base being exposed between at least some of the pattern elements but a major portion of the base being covered.

5. As a new article of manufacture, a surface covering comprising a base made up of a fabric web and having a substantially continuously extending layer of linoleum mix thereover, said layer being of substantially uniform thickness, and pattern elements of linoleum mix overlying the base and secured thereto, the base being exposed between at least some of the pattern elements.

6. As a new article of manufacture, a surface covering comprising a base made up of a fabric web and a substantially continuously extending layer of linoleum mix thereover, and pattern elements of linoleum mix overlying the base, the pattern elements being in the form of tiles and the base being exposed between at least some of the pattern elements.

45 7. As a new article of manufacture, a surface covering comprising a base made up of a fabric web, a substantially continuously extending layer of linoleum mix thereover, and pattern elements of linoleum mix overlying the base, the pattern elements being relatively large in number, there being a plurality of such elements both crosswise and longitudinally of the material, the base being exposed between at least some of the pattern elements.

8. As a new article of manufacture, a surface covering comprising a base made up of a fabric web, a substantially continuously extending layer of linoleum mix thereover, and pattern elements of linoleum mix overlying the base, the pattern elements being relatively large in number, there being a plurality of such elements both crosswise and longitudinally of the material, the base being exposed between at least some of the

pattern elements and lying at a lower level than the top surface of said pattern elements.

In testimony whereof I have hereunto set my hand.

CHARLES F. HUMPHREYS.
